APPARATUS FOR TWISTING FILAMENTS,
THREADS, BANDS, AND THE LIKEEric Andrew Morton, Coventry, England, assign-
or to Courtaulds Limited, London, England, a
British companyApplication May 6, 1939, Serial No. 272,247
In Great Britain May 16, 1938

2 Claims. (Cl. 57—58)

This invention relates to apparatus for twisting filaments, threads, bands and the like (hereinafter referred to as threads) and in particular to that type of apparatus in which the thread is twisted in the following manner: the thread is drawn off from a package such as a bobbin, cake or cheese (hereinafter referred to as the delivery bobbin) passed through a rotating spindle, then guided in the reverse direction forming a balloon round the delivery bobbin and is wound on to a suitable collecting device. If the delivery bobbin is kept stationary, two turns of twist are imparted to the thread for each revolution of the spindle.

In order to maintain the delivery bobbin stationary while the spindle rotates, various methods have been proposed. For example it has been proposed to use magnetic means, such as an iron plate attached to one end of the bobbin carrier and an electro magnet to attract this plate continuously. It has also been proposed to use a weight which may be attached to the delivery bobbin holder, or to the thread guide, or may be loosely mounted or suspended in the latter, or loosely suspended in the delivery bobbin holder. It has also been stated, however, that in practice it is often found that the delivery bobbin holder or support tends to oscillate upon the spindle and that this oscillation may be obviated by constructing the bobbin support with parts between which relative movement is adapted to take place, if and when circumstances arise under which the bobbin and its holder tend to oscillate.

The object of the present invention is to provide an improved apparatus for twisting thread in the manner hereinbefore described, wherein movement of the delivery bobbin is substantially prevented by a device of the suspended weight type.

According to the present invention the said improved apparatus comprises a rotatable hollow spindle and mounted thereon a conical thread guide and a delivery bobbin support, which support is prevented from rotating with the spindle by means of a weight, wherein the weight comprises a hollow element partly filled with a liquid.

The liquid is preferably of high specific gravity, such for example as mercury, particularly when the apparatus is to be used for twisting threads of low denier when only a relatively small balloon is formed. The weight may be attached to the delivery bobbin support or incorporated therewith in any desired way. For example, it may be attached to, or form part of,

the conical thread guide, if the latter is loosely mounted on the rotatable spindle and is attached to the delivery bobbin support. Alternatively, it may be attached both to a sleeve or collar loosely mounted on the said spindle and to the delivery bobbin support. 5

The conical thread guide may be loosely mounted on the rotating spindle or may be fixed thereto. If desired, a cylindrical or conical shield made for example of a transparent material, such as cellulose film, may be placed between the delivery bobbin and the balloon of the thread formed between the conical thread guide on the rotating spindle and the collecting device. 15

The accompanying diagrammatic drawing illustrates by way of example one arrangement of apparatus according to the present invention although the invention is not restricted to the arrangement shown. 20

Figure 1 is a side elevation partly in section and Figure 2 is a section on the line 2—2 in Figure 1.

A spindle 1 is journaled on ball bearings 2 in a support 3 and can be rotated by means of a belt drive around the pulley 4. On the spindle 1 a conical thread guide 5 is fixed. The spindle 1 is hollow and connects with a radial passage 6 in the guide 5. A sleeve 7 is loosely mounted by means of ball bearings 8 on the spindle 1 inside the thread guide 5 and hanging from the sleeve 7 and rigidly connected thereto is a hollow member 9 containing mercury 10. Fixed on top of the member 9 is a thread tensioning device 11. A bobbin holder consisting of a disc 12, a hollow 25 spindle 13 and a transparent shield 14 is rigidly connected with the end of the member 9. The thread 15 is led from the bobbin 16 through the hollow spindle 13, chafing of the thread on the end of the bobbin being minimised by means of 30 a polished aluminium disc 17 fitting over the end of the bobbin, through the device 11 and the hollow spindle 1, along the passage 6 and then in the reverse direction, over the guide 5, through a guide 18 to a winding up device which is not shown. The spindle 1 is caused to rotate by the belt drive on the pulley 4 and rotates in turn the thread guide 5 and the thread, passing through the passage 6, so that the thread 35 describes a surface of rotation or "a balloon" between the guides 5 and 18. Although the bobbin is in effect supported on the rotating spindle 1 oscillation of the bobbin is almost completely prevented by the hanging liquid weight 10 and a 40

very high speed of winding and twisting can be attained.

What I claim is:

1. Apparatus for twisting thread in the manner hereinbefore described comprising a rotatable hollow spindle and mounted thereon a conical thread guide and a delivery bobbin support, which support is prevented from rotating with

the spindle by means of a weight, wherein the said weight comprises a hollow element partly filled with a liquid.

2. Apparatus as claimed in claim 1, wherein the liquid contained in the hollow element is mercury. 5
